UNITED STATES PATENT OFFICE.

MATHIAS J. LA RIVIERE, OF WATERBURY, CONNECTICUT.

STOP SIGNAL.

Application filed July 17, 1924. Serial No. 726,568.

This invention relates to signals for automobiles and more particularly to that type of device adapted to be mounted preferably at the rear of the machine for warning those following the machine as to its future progress or direction of movement.

One of the objects of the present invention is to provide a simple device of the above character having a plurality of signaling devices operable at will from the driver's seat.

A further object is to provide a practical, and compact, construction of the above character, which may be inexpensively manufactured, assembled and installed.

15 A further object is to provide a device of the above character having a plurality of independently operated indicating signals actuated at will by the driver, thereby to prevent confusion.

20 Other objects will be in part obvious and in part hereinafter pointed out in connection with the accompanying sheets of drawings forming part of this disclosure, and in which drawing corresponding parts are indicated by similar reference characters throughout the several views.

In these drawings, Figure 1 is an elevational view showing the device in operative position and the wiring circuits in diagram; 30 Figure 2 is a vertical central sectional view; and

Figure 3 is a sectional view taken on the line 3—3 of Figure 2.

Referring now to the drawings in detail, 35 and more particularly to Figure 1, 5 indicates a portion of an automobile, such as the side above the rear fender, although, of course, it is to be understood that the present device may be applied to the rear central part of the machine or elsewhere, if so desired. The signal device casing, indicated at 6, is adapted to be attached to this support or body 5 in any desired manner, such, for example, as by means of the plate 7, fastening bolts 8 40 and tubular connecting member 9. The casing 6 is preferably made elliptical or circular for ease and cheapness of manufacture, and also thereby to present a relatively small compact mass. This case is provided with 45 metallic protecting surfaces 10 secured in place by means of flanged-over edges 11 of the casing 6. Behind these metallic surfaces are translucent ground glass plates 12, the rear one of which is preferably red and provided 50 with four indicators, two of which are ar-

rows indicating right and left turns, while the top and bottom indicate "Stop" and "Slow". The outer surfaces of the front and rear glass plates are colored red and the inside surfaces colored black with black surface cut-out or stenciled to form red letters desired so the resulting color effect is such that the letters are only distinctive when light is lighted. The interior of the casing 6 is provided with a plurality of compartments formed by horizontal partitions 13, having upstanding end portions 13^a secured to the interior of the casing in any approved manner and extending along said casing to strengthen the same. Bent inwardly from the portions 13^a are extensions 13^b, to which horizontal partition members 13' are secured. In the central compartment, I secure the vertical partition members 14 between and to the adjacent horizontal positions 13 and 13'. Each chamber is provided with a lamp 15 immediately behind the indicating signals, as shown in Figure 1. Thus, the upper chamber is provided with the word "Stop" and the lower chamber with the word "Slow" while the two central chambers, 80 provided with indicating arrows pointing to the right and left, clearly indicate the direction or progress of the car as shown in Figure 1.

Each one of the lamps is connected by suitable wiring with a battery 16 and a switch board 17 provided with various buttons 18 which may be operated at will to indicate the desired signal. As long as the buttons are depressed, the proper signal will be illuminated. The partitions 13 and 14 separate the interior of the casing, in such a manner as to prevent the light emitted from one lamp 15 showing through an adjacent signal. Also the partition constitutes supports for the several bulbs. By having the front of the casing closed by red letters on a black surface a warning is given to approaching cars, which is especially desirable when making a left turn.

It will thus be seen that the present invention constitutes a simple and practical stop signal device which may be inexpensively manufactured and assembled.

I claim:

In a device of the character described, a casing adapted to contain signal lamps and having open ends, horizontal partition members extending across said casing and having upstanding portions engaging with the in-

ner surface of said casing, inward extensions on said portions, other horizontal partition members secured to said extensions, vertical partition members extending between and 5 secured to adjacent horizontal partition members forming a plurality of compartments in said casing, and glass plates disposed in the

open ends of said casing and closing said compartments, said partition members providing a mounting for the signal lamps in 10 said compartments.

Signed at Waterbury, Connecticut, this 12th day of July, 1924.

MATHIAS J. LA RIVIERE.
